UNITED STATES PATENT OFFICE.

CHARLES BISHOP, OF TACOMA, WASHINGTON.

SMELTING-FURNACE.

SPECIFICATION forming part of Letters Patent No. 578,963, dated March 16, 1897.

Application filed October 23, 1896. Serial No. 609,821. (No model.)

To all whom it may concern:

Be it known that I, CHARLES BISHOP, of 5
Tacoma, in the county of Pierce and State of
Washington, have invented a new and Im-
proved Smelting-Furnace, of which the fol-
lowing is a full, clear, and exact description.

The object of the invention is to provide a
new and improved smelting-furnace more
especially designed for fusing all kinds of ore
10 and arranged to permit of using oil as the fuel,
with or without charcoal mixed in the ore.

The invention consists of certain parts and
details of the same, as will be fully described
hereinafter and then pointed out in the claims.

15 Reference is to be had to the accompanying
drawings, forming a part of this specification,
in which similar characters of reference indi-
cate corresponding parts in all the figures.

Figure 1 is a sectional side elevation of the
20 improvement on the line 1 1 of Fig. 3. Fig.
2 is a transverse section of the same on the
line 2 2 of Fig. 3. Fig. 3 is a sectional plan
view of the same on the line 3 3 of Fig. 1.
Fig. 4 is an enlarged sectional side elevation
25 of one of the fire-boxes, the section being
taken on the line 4 4 of Fig. 5; and Fig. 5 is a
sectional plan view of the same on the line
5 5 of Fig. 4.

The improved smelting-furnace is provided
30 with a suitably-constructed stack A, in the
lower end of which is arranged an inclined
grate B, preferably made of hollow pipes,
through which circulates water supplied by
a pipe B', connected with a suitable water-
35 supply. On the grate B rests the charge of
ore, mixed, if desired, with charcoal, the
charge being introduced into the stack by a
charge-door C, built in one side of the brick-
work a suitable distance above the grate, as
40 shown in the drawings. Below the grate B is
formed a combustion-chamber D, into
which open a series of fire-boxes E, deriving
their supply of fuel in the form of oil from
oil-tanks F, arranged exteriorly of the stack
45 and a suitable distance above the fire-box, so
that the oil flows by its own gravity through
a valved pipe F' into the fire-box to be burned
therein, the flame passing into the combus-
tion-chamber under the grate B to heat and
50 melt the ore supported thereon. The bottom
of the combustion-chamber D is formed into
a basin or bowl G, adapted to receive the

molten metal dropping between the pipes or
bars of the grate B through the combustion-
chamber into the said bowl G. The latter is 55
connected at its bottom by an inclined chan-
nel G' with a bullion-pot H, built in the brick-
work of the stack A, and the bullion-pot is
provided with an outlet H', usually closed by
a plug, unless it is desired to run the bullion 60
off very rapidly.

The upper end of the bowl or basin G is con-
nected with a slag-discharge I, extending to
one side of the furnace and having a bottom
inclined downwardly and outwardly, to read- 65
ily run off the slag accumulating on the top
of the molten metal contained in the basin G.
The slag-discharge I is closed near its lower
end with a door I', opened from time to time
to run off the slag. 70

The combustion-chamber D has its walls
formed with offsets relative to the lower end
of the stack A, so that the molten metal can
drop through the combustion-chamber and
accumulate in the bowl G, and the upper or 75
inner end of the slag-discharge I is likewise
set off, so as to cause the slag on the top of
the molten metal to readily pass into the said
slag-discharge without danger of the molten
metal passing into the said discharge. 80

The lower portion of the grate B extends
into the bottom of a discharge-chamber J,
normally closed by a door J' and adapted to
receive the residue or slag of the ore sliding
down the grate B after the metal has been ex- 85
tracted from the ore. It will be seen that
by the arrangement described the substances
contained in the ore and not forming part of
the metal are separated from the molten metal
by passing down the grate B into the cham- 90
ber J, from which the waste slag or residue
can be removed from time to time through
the door J'. 95

Each of the fire-boxes E is preferably of
the construction shown in detail in Figs. 4
and 5, that is, the end of the pipe F' dis-
charges upon porous fireproof brick E', so that
the oil saturates this brick and the latter
evaporates the oil, the vaporizing being done
in a chamber E², built in the brickwork of the 100
furnace.

In order to prevent the flame from passing
backward, I erect in the rear of the brick E'
a reflecting-bridge E³ to cause the burning

gases to pass through openings or slots E⁴ in the front of the chamber E³ into the combustion-chamber D, the said slots or openings E⁴ being formed by bricks E⁵, set at suitable distances apart. Air passes to the chamber E² by a channel E⁶.

Now it will be seen that by the arrangement described the heat from the burning oil readily passes into the combustion-chamber 10 D and upward between the bars of the grate B to the charge, so as to heat and melt the metal contained therein, the molten metal dropping between the bars of the grate into the basin or bowl G, in which the slag is separated and discharged by the slag-discharge 15 I. The pure molten metal runs through the channel G' into the bullion-pot H, from which it is removed from time to time, the said bullion-pot being open at the top by a niche 20 built in the side of the furnace, as plainly indicated in Figs. 2 and 3. If the molten metal runs very fast into the bowl G, it can be run out directly by removing the plug from the outlet H'.

25 Having thus fully described my invention, I claim as new and desire to secure by Letters Patent--

1. A smelting-furnace, comprising a stack, a combustion-chamber having its bottom 30 formed into a basin to receive the molten metal, a slag-discharge chamber, an inclined grate, the lower end of which projects into the said slag-discharge chamber, and a plurality of fire-boxes connected with an oil-supply 35 and discharging into the combustion-chamber, substantially as described.

2. A smelting-furnace, comprising a stack, a grate at the lower end of the stack and arranged in an inclined position, a combustion- 40 chamber under the grate, a slag-discharge chamber, into which the lower end of the grate projects a series of fire-boxes discharging into the said combustion-chamber from the sides thereof and each formed with a vaporizing-chamber, and a basin forming the 45 bottom for the said combustion-chamber and adapted to receive the molten metal dropping through the grate and combustion-chamber, substantially as shown and described.

50 3. A smelting-furnace, comprising a stack, a grate at the lower end of the stack and arranged in an inclined position, a discharge-chamber into which one end of the grate projects, a combustion-chamber under the grate,

a series of fire-boxes discharging into the said 55 combustion-chamber from the sides thereof and each having a vaporizing-chamber, a basin forming the bottom for the said combustion-chamber and adapted to receive the molten metal dropping through the grate and 60 combustion-chamber, a bullion-pot connected with the said basin, substantially as shown and described.

4. A smelting-furnace, comprising a stack, a grate at the lower end of the stack and arranged in an inclined position, a combustion-chamber under the grate, a series of fire-boxes discharging into the said combustion-chamber from the sides thereof and each formed 65 with a vaporizing-chamber, a basin forming 70 the bottom for the said combustion-chamber, and adapted to receive the molten metal dropping through the grate and combustion-chamber, and a slag-discharge leading from the upper end of the said basin to the outside 75 of the furnace and into which the lower end of the grate projects, substantially as shown and described.

5. A smelting-furnace, comprising a stack having a charge-door located a suitable distance above the lower end of the stack, an inclined grate arranged in the bottom of the said stack and leading to a slag-chamber, a combustion-chamber under the grate, a series of fire-boxes opening into the said combustion-chamber from the sides thereof, a basin 80 forming the bottom for the said combustion-chamber and having a metal-discharge channel in its bottom and a slag-discharge at its upper portion, and a bullion-pot connected 85 with the said basin, substantially as shown and described.

6. A smelting-furnace, provided with a fire-box comprising hollow porous brick, an oil-feed pipe discharging into the said brick and 90 connected with an oil-tank, a reflector for the said brick and located in the rear thereof, and a chamber connected with an air-supply and containing the said brick and reflector, the said chamber having a series of openings 95 leading from the chamber to a combustion-chamber, substantially as shown and described.

CHARLES BISHOP.
